UNITED STATES PATENT OFFICE.

THOMAS I. LUDWIG, OF DETROIT, MICHIGAN.

GARMENT SUPPORT.

Application filed October 10, 1923. Serial No. 667,763.

To all whom it may concern:

Be it known that I, THOMAS I. LUDWIG, a citizen of the United States, residing at Detroit, in the county of Wayne and State of Michigan, have invented a new and useful Garment Support, of which the following is a specification.

This invention relates to garment supporters and aims to provide novel means 10 to be supported by the usual belt, for contacting with the body of the wearer to support the garment by frictional contact.

Another object of the invention is to provide a device of this character which will 15 be readily and easily secured to a belt, the device being such as will conform to the curvature of the body of the wearer.

A still further object of the invention is to construct the device in such a manner 20 as to insure against displacement thereof with respect to the supporting belt.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 within the scope of what is claimed, without departing from the spirit of the invention.

Referring to the drawing:

Figure 1 is an elevational view disclosing a portion of a belt supplied with a 30 supporting device constructed in accordance with the device.

Figure 2 is a sectional view taken on line 2-2 of Figure 1.

Figure 3 is a sectional view taken on line 40 3-3 of Figure 1.

Figure 4 is a modified form of the support.

Figure 5 is a still further modified form of the invention.

Referring to the drawing in detail, the reference character 5 designates the belt which is of the usual construction and to which the auxiliary supporting strap 6 is secured as by lines of stitching 7, disposed 45 along the edges of the belt, leaving the central portion of the auxiliary strap free to move with respect to the belt 5.

Spaced openings 8 are formed in the auxiliary strap 6 which openings accommodate the curved extremities 9 of the sup-

porting wire 10 which includes a curved body portion formed with upwardly and downwardly extended end portions 11 terminating in the curved extremities 9 as clearly shown by Figures 1 and 3 of the drawings.

Positioned on the body portion of the supporting wire 10 is a tubular member 12 formed preferably of rubber so that the tubular member may be readily and easily 65 positioned over the wire 10. As shown more clearly in Figure 2 of the drawing, the wire 10 is curved to conform to the curvature of the body of the wearer adjacent to the hip, whereby the curved tubular member 12 may, by its frictional contact hold the belt 5 and garment supporting the same, in its proper position.

Should it be desired to adjust the supporting devise, with respect to the auxiliary strap 6 the ends 9 of the wire 10 may be removed from the openings and positioned in adjacent openings to the comfort of the wearer.

In the modified form of the invention as 75 illustrated by Figure 4 of the drawing, the supporting wire which is indicated at 13 includes a length of wire bent upon itself as clearly illustrated in dotted lines to lend resiliency to the support, the ends of the wire extending upwardly and downwardly as at 14 where they terminate in right angled extremities 15 designed to be fitted within certain openings of the auxiliary strap.

A tubular member 16 is also formed of suitable flexible material and is positioned over the wire to frictionally engage the body of the wearer. In Figure 5 I have 85 illustrated a further modified form of the invention which includes a supporting body 17 on which the rubber covering 18 is mounted, the ends of the body portion 17 being bent around the curved wire 19 which is also curved and extended downwardly 100 to engage that portion of the wearer's shirt extending below the waist line.

The wire 19 is also covered by a tubular covering 20 to increase the friction between the wire and that portion of the shirt of the wearer engaged thereby. Securing wires 21 extend into the covering 18 and disposed between the covering and body 17, the ends of the securing wires 21 being 105 curved rearwardly as at 22, where they are 110

formed with hooks 23 designed to be positioned in the openings of the auxiliary strap to support the same.

From the foregoing it will be obvious that the supporting device as shown and described, will efficiently support a garment to which the same is supplied by its frictional contact with the body of the wearer at points adjacent to the hips of the wearer.

It will also be seen that due to the construction and location of the member 19 the lower portion of the shirt of the wearer will be held down by frictional contact of the member 20 with the shirt.

I claim:—

1. In a device of the character described, a supporting belt, an auxiliary supporting strap secured to the belt and having a plurality of spaced openings, a supporting member having curved extremities adapted to be positioned in the openings and lie between the supporting strap and belt and a covering for said supporting member.
2. In a device of the character described,

a supporting belt, an auxiliary supporting strap secured to the belt and having openings formed therein, a curved supporting wire having upwardly and downwardly extended end portions terminating in right angled extremities adapted to be positioned in the openings, and a covering of flexible material disposed over the curved wire to frictionally engage the body of the wearer.

3. In a device of the character described, a supporting belt, a strap secured to the supporting belt and having openings, a body portion including a length of wire bent upon itself and having curved ends terminating in right angled portions adapted to be positioned in the openings of the strap, and a cover of flexible material positioned on the body portion.

In testimony that I claim the foregoing as my own, I have hereto affixed my signature in the presence of two witnesses.

THOMAS I. LUDWIG.

Witnesses:

HENRY O. BEARD,
STELLA ASAM.
